UNITED STATES PATENT OFFICE.

HENRY A. HANSEN AND ROY W. HANSEN, OF CHICAGO, ILLINOIS.

DESIGN FOR A LAMP PHONOGRAPH.

Application filed February 13, 1922. Serial No. 681. Term of patent 7 years.

To all whom it may concern:

Be it known that we, HENRY A. HANSEN and Roy W. HANSEN, citizens of the United States, residing at Chicago, in the county of Cook and State of Illinois, have invented a new, original, and ornamental Design for Lamp Phonographs, of which the following is a specification, reference being had to the accompanying drawing, forming a part thereof.

The figure is an elevation of the lamp.

We claim:

The ornamental design for a lamp phonograph as shown.

HENRY A. HANSEN.
ROY W. HANSEN.
